C. H. ALLEN

METHOD AND MEANS FOR PRINTING RAISED FIGURES AND THE LIKE

Filed Jan. 15, 1926

UNITED STATES PATENT OFFICE.

CHARLES H. ALLEN, OF PITTSBURGH, PENNSYLVANIA.

METHOD AND MEANS FOR PRINTING RAISED FIGURES AND THE LIKE.

Application filed January 15, 1926. Serial No. 81,537.

This invention relates to methods and means for printing raised letters and more in particular for printing figures and letters on dials.

5 The primary object of this invention is to provide a method and means for the rapid printing of letters, figures and designs in raised forms to imitate results now obtained especially by the method of embossing on 10 business-cards, letterheads and other kinds of printed matter. Another important object is to provide means for printing figures and letters on clock, and other, dials with semi-liquid printing compositions, such as 15 radium compositions, for making luminous figures or designs on clock-dials or other dials used on measuring instruments and so forth. A further object of this invention is to provide means for printing figures 20 with such materials by means of compressed air, and also to provide means which automatically interrupt the supply of compressed air to the printing composition after each printing operation. Additional 25 features and advantages of this invention will appear from the following description considered in connection with the accompanying drawing, forming part of this application and in which:—

30 Fig. 1 shows diagrammatically a complete printing outfit built in accordance with this invention.

Fig. 2 is a fractional detail view showing 35 a special clutch-operating mechanism used in Fig. 1 and which shall be described later.

Fig. 3 is an enlarged view showing the printing device proper.

40 Fig. 4 is a fragmentary bottom view of one type of printing die used in connection with this invention.

Fig. 5 shows in perspective an enlarged view of one of the figures of the printing-die shown in Fig. 4.

45 Fig. 6 is a cross section through the cam operated air-supply-valve used in Fig. 1.

Fig. 7 is a similar view of the air-discharge-valve.

50 Fig. 8 is a section taken on line 8—8 in Fig. 5 showing a die-feeding tube greatly enlarged.

Fig. 9 is a fragmentary section showing a different method of making the figures in the printing die by the engraving-process.

55 Fig. 10 shows another modification adapt-

ed especially for engraving the figures or symbols in small die-plates.

Heretofore, the printing of raised figures, such as luminous figures on dials, has been performed completely by hand or by stenciling, which latter process, owing to the nature of the printing composition used, and the thickness thereof needed for effective luminous radiation, requires a great amount of time for retouching purposes. The present invention performs the printing of said figures with the same kind of printing composition by means of a novel type of die shown in particular in Figs. 3, 4, 5, 9 and 10.

Referring to these figures and assuming that the figures for a clock-dial are to be printed with a luminous compound, the printing element comprises a die-plate 1 upon which are properly disposed the individual dies 2 for the figures. Said figure-dies comprise outer walls 3 and inner walls 4, suitably bent or engraved to reproduce the desired figures. The radium composition required for printing is introduced between the walls of the figure-dies by means of small feed-tubes 5 or holes 5^a, disposed substantially half-way between said walls and driven right through the die-plate if tubes are used, or drilled if holes are used. In the former case the tubes are set back a certain distance from the working edges 6 of the walls to enable a ready flow of the composition therebetween. The height or thickness of the printed figures is determined by the height of the walls of the figure-dies, as will be understood.

The printing composition is introduced in a container 7, comprising the side 8 provided with the flange 9 whereby the container is secured to a frame 10 by means of the screws 11. This container is closed at the bottom by the die-plate 1 which is secured by screws 12 or other suitable and desired means. A gasket 13 is preferably made use of to insure a tight connection between the die-plate and flange.

The container has at the top a removable cover 14 having a gasket 15, which is clamped in place by means of the hinge-bolts 16 and their wing nuts 17. At the center of this cover there is provided a stuffing-box 18, of usual design, through which passes the vertical shaft 19 of the stirring device or agitator 20. The shaft is guided

for rotation in a bearing 21 formed on a support 22, having a bracket 23 upon which an electric motor 24 may be mounted to operate the agitator. The power of said motor is transmitted to the shaft 19 by means of speed reducing gears represented by the bevel-gears 25.

The printing composition is introduced into the container either by removing the 10 cover 14, or through a suitable aperture 26, which is closed by a threaded plug 27.

Said composition is forced through the feed tubes 5, or through the apertures 5^a as the case may be, by compressed air which 15 is introduced in the container by the elbow connection 28 screwed in the top cover. This air may be obtained from any suitable source, such as a pressure storage tank, or from a special compressor plant as shown 20 in Fig. 1. This air compressing apparatus comprises an electric motor 29 connected to an air compressor 30 which delivers the compressed air into a storage tank 31 whence it is led into the container 7 through 25 a pipe connection 32 into which a regulating valve 33 is preferably placed to adjust the pressure and amount of compressed air delivered into said container.

The blank sheet or dial upon which the 30 luminous figures are to be printed is first set in a holding device of suitable shape and construction to hold said blank, such as the template 34, mounted upon a vertically movable table 35 provided with a central rod 36 slidably mounted in a bearing 37 forming part of the frame 10. The blank is then pressed against the figure-dies by raising the table 35 and the printing compound is finally forced on said blank dial or sheet by letting 40 the compressed air act on the compound in the container and forcing out the compound onto the blank. After a sufficient amount of the compound has been deposited on the blank, the compressed air in the container 45 is released, the table is then lowered to enable the removal of the now printed blank and the insertion of a new blank.

In order to expedite the printing process, for quantity manufacture, most of the above 50 mentioned operations are quickly performed semi-automatically by means of the following mechanism: Hingedly connected to the lower end of the rod 36 by means of the pin connection 38 is a lever 39 suitably fulcrumed at 40 and having at its other end 41 an antifriction roller 42. The latter rides upon a cam 43 the periphery of which has substantially the shape shown in Fig. 1. This cam is secured upon a shaft 44 which is 55 rotatably mounted in a bearing 45 provided in the standard 46 and which may be connected to the shaft of an electric motor 47 by means of any suitable device, such as the clutch-coupling 48 having one half keyed 60 on the motor shaft 49 while the other half

is slidably held on shaft 44 by means of an ordinary feather key 50.

Upon the shaft 44 is also secured a sprocket 51 which is connected by a chain drive 52 to another sprocket 53 of equal diameter keyed upon a shaft 54 running in a bearing 55 located in the upper part of the standard 46. On the other side of this bearing are keyed on the shaft a spur gear 56 and a cam 57. Upon the latter rides the lower end of the valve-stem 58 of the air supply valve 59, the construction of which, as shown in Fig. 6, is such that the valve will be opened when the stem 58 is raised by the cam.

In mesh with gear 56 is another gear 60 of the same size. The latter is secured on the shaft 61 upon which is also keyed a cam 62 which is engaged by the stem 63 of the air discharge valve 64, shown especially in Fig. 7. The cams 57 and 62 are mounted in opposite direction so that when the valve 59 is opened, valve 64 will remain shut, and vice versa.

As will be readily understood, compressed air must be introduced in the container 7 only when the blank dial is pressed against the die-plate 1. Also when the table 35 is dropped, no compressed air should be present in the container in order to prevent waste of the printing composition.

The operation of the valves 59 and 64 is effected automatically in the desired time relation in the following manner: At the outer end of the lever arm 41 is hingedly secured the link 65 the lower end of which is rockably connected by the pin connection 66 to a lever 67 fulcrumed at 68 on the standard 46. The opposite end of this lever connects by means of a pin connection 69 to the substantially T-shaped lever 70 rockably mounted at 71 on an extension 72 provided on said standard. The upper arm 73 of the lever 70 terminates at the top with a fork 74 which is provided with the usual means required to slide the movable half of the coupling 48 into or out of engagement with the motor-half thereof. The third arm of the lever 70 is connected by means of the pull-rod 75 to a pedal 76 suitably mounted on the floor.

Based on the following description, the operation of the device will be readily understood, it is as follows: Assuming that the table be in the lowered position shown in Fig. 1, that a blank dial has been set thereon to be printed and that the electric motors be all running, the operator presses on the pedal 76 for just a sufficient time to cause the movable half of the clutch coupling to engage the motor-half whereby the shaft 44 is rotated. This operation causes also the lever 39 to rotate clockwise thus forcing the blank dial against the die-plate 1. Simultaneously the rotation of the shaft 44 is

transmitted, through the chain drive 52, to the cam 57 which opens the valve 59 while the discharge valve 64 is kept shut by its internal spring 79.

- 5 The compressed air is therefore enabled to act on the printing composition stored in the container and said composition will be forced through the feed tubes 5 and deposited in the form of figures on blank dial. 10 In the meanwhile the roller 42 follows the contour of the rotating cam 43 until it drops into the recess 77 under the influence of the weight of the table 35, assisted by the coil spring 78 acting on the lever 39. This motion is transmitted by the link 65 and the lever 67 to the T-lever 70 which is caused to rotate counter clockwise, thus disconnecting the clutch coupling. Simultaneously the supply valve 59 has been shut by its spring 20, the discharge valve 64 opened to release the air in the container and the table 35 lowered to remove the printed dial and insert a new blank dial. The same process would be started again by first pressing 25 down the pedal 76.

In the present embodiment of my invention I have shown the use of three distinct motors to operate various parts of the printing plant. In practice, however, one single 30 motor could be made to perform all the required operations by introducing in the construction suitable modifications which would require only mechanical skill to devise.

As will be understood, as suggested herein, 35 there may be slight changes made in the construction and arrangement of the details of my invention without departing from the field and scope of the same, and I intend to include all such variations as fall within 40 the scope of the appended claims, in this application in which the preferred forms only of my invention are disclosed.

I claim:

1. In a press for printing raised figures and the like on a blank, the combination of a container for the printing compound; a die-plate forming the bottom of said container, a plurality of hollow dies positioned on said die-plate and having the shape of said figures; a plurality of feed-tubes positioned within said hollow-dies and in communication with said container, means to exert a fluid pressure on said compound during the printing period of said dies and means adapted to release said fluid pressure during the non-printing period of said dies.
2. In a press for printing raised figures

and the like on a blank, the combination of a container for the printing compound; a die-plate forming the bottom of said container; a plurality of hollow dies positioned on said die-plate and having the shape of said figures; a plurality of feed-tubes positioned within said hollow-dies and in communication with said container; a table for said blank; means to move said table into and out of engagement with said hollow-dies, means to exert a fluid pressure on said compound during the engagement of said table with said hollow-dies and means to release said fluid-pressure just before said engagement is broken.

3. In a press for printing raised figures and the like on a blank, the combination of a container for the printing compound; a die-plate forming the bottom of said container; a plurality of hollow dies positioned on said die-plate and having the shape of said figures; a plurality of feed-tubes positioned within said hollow-dies and in communication with said container; a table for said blank; means to move said table into and out of engagement with said hollow-dies, means to exert a fluid pressure on said compound during the engagement of said table with said hollow-dies and means to automatically release said fluid-pressure just before said engagement is broken.

4. In a press for printing raised figures and the like on a blank, the combination of a container for the printing compound; a die-plate forming the bottom of said container, a plurality of hollow dies positioned on said die-plate and having the shape of said figures; a plurality of feed-tubes positioned within said hollow-dies and in communication with said container; a table for said blank; means to move said table into and out of engagement with said hollow-dies, said means comprising a rod, a lever hingedly connected thereto and a cam; a shaft for said cam; means to rotate said cam-shaft; a source of compressed air, an air supply valve, an air release valve; means actuated by said cam-shaft to open said supply valve when said table is in engagement with said hollow-dies and to open said release-valve just before said engagement is broken, and means actuated by said lever to stop the rotation of said cam-shaft simultaneously with the opening of said release valve.

In testimony whereof I affix my signature.
CHARLES H. ALLEN.
